UNITED STATES PATENT OFFICE.

EDWIN V. BABBITT, OF FAIRHAVEN, MASSACHUSETTS, ASSIGNOR TO INTERNATIONAL TOY CORPORATION, OF NEW BEDFORD, MASSACHUSETTS, A CORPORATION OF MASSACHUSETTS.

DESIGN FOR A TOY SEA SCOOTER.

Application filed June 8, 1926. Serial No. 17,989. Term of patent 14 years.

To all whom it may concern:

Be it known that I, EDWIN V. BABBITT, a citizen of the United States, residing at Fairhaven, in the county of Bristol and State of Massachusetts, have invented a new, original, and ornamental Design for a Toy Sea Scooter, of which the following is a specification, reference being had to the accompanying drawing, forming a part thereof.

In the drawing,—

Figure 1 is a perspective view of a toy sea scooter showing my new design;

Figure 2 is a top plan view, and Figure 3 an end view, of a toy sea scooter showing my new design.

I claim:

The ornamental design for a toy sea scooter substantially as shown.

EDWIN V. BABBITT.
